(57) **CLAIM**

The ornamental design for a front cover and display for a wireless communications device, as shown and described.

DESCRIPTION

FIG. 1 is a perspective view of a front cover and display for a wireless communications device of the present invention; FIG. 2 is a front elevational view thereof; FIG. 3 is a left side elevational view thereof; FIG. 4 is a right side elevational view thereof; FIG. 5 is a top plan view thereof; and, FIG. 6 is a bottom plan view thereof.

The broken line showings throughout the views are for illustrative purposes only and form no part of the claimed design.
